UNITED STATES PATENT OFFICE.

EDWIN A. STRATTMAN, OF BOGALUSA, LOUISIANA.

SAFETY-TURRET FOR EXPRESS-CARS.

1,119,468.

Specification of Letters Patent.

Patented Dec. 1, 1914.

Application filed October 7, 1913, Serial No. 793,840.

To all whom it may concern:

Be it known that I, EDWIN AUGUST STRATTMAN, a citizen of the United States, residing at Bogalusa, in the parish of Washington and State of Louisiana, have invented certain new and useful Improvements in Safety-Turrets for Express-Cars; and I do hereby declare the following to be a full, clear, and exact description of the invention, such as will enable others skilled in the art to which it appertains to make and use the same.

My invention relates to devices adapted to be placed in railway, baggage and express cars or in banks and other places where large sums and valuables are contained so that the sums and valuables may be properly guarded against robbery.

An important object of my invention is to provide a turret so constructed that should the train be held up by robbers for the purpose of plunder the express agent may step to the turret and from his position defend the contents of the car with fire arms and will be protected from injury by the robbers.

A further object is to provide novel means in connection with the turret for permitting the defender of valuables, etc. to train the fire arms at any point within the car or building in which the safety turret is placed.

A still further object is to provide a device such as described which consists of few parts, may be readily placed in position, is reliable and efficient in its operation and cheap to manufacture.

The above and additional objects are accomplished by such means as are illustrated in the accompanying drawings, described in the following specification and then more particularly pointed out in the claims which are appended hereto and form a part of this application.

With reference to the drawings, wherein, I have illustrated the preferred embodiment of my invention as it is reduced to practice, and throughout the several views of which, similar reference numerals designate corresponding parts: Figure 1 is a vertical sectional view illustrating the turret in assembled position, Fig. 2 is a top plan view illustrating the ventilating means afforded at the top of the turret. Fig. 3 is a transverse sectional view taken on line 3-3

of Fig. 1, Fig. 4 is a cross sectional view taken on line 4-4 of Fig. 1 illustrating in detail one of the fire arms supporting spheres and the manner of securing the same to the turret, Fig. 5 is a detail view of one of the connecting braces, Fig. 6 is a detail sectional view of one of the fire arms supporting spheres, and Fig. 7 is a rear elevation partly in section of one of the supporting spheres illustrating the means for securing the fire arm to the sphere.

Proceeding now to the description of the drawings the numeral 1 designates as an entirety the turret which consists of a plurality of cylindrical metallic bullet proof sections and is of sufficient size and height to permit the free movement of a person or persons therewithin.

In the drawings I have illustrated the turret consisting of three cylindrical sections, the bottom or base section 2, that is secured to the floor of the building or car through the instrumentality of a plurality of spaced ears 3 formed integral with the lower terminal thereof and extending inwardly and screws or other suitable fastening means 4 that are inserted through the ears 3 and have threaded engagement with the floor, a top section 5 that is supported in spaced relation to the bottom section 2 by means of the vertical supporting braces 6, 7 and 8, and a revoluble section that is disposed approximately centrally of the upper and lower terminals of the sections 2 and 5 and supports the fire arms in a manner which will be hereinafter more fully described.

Formed integral with the upper terminal of the lower section 2 is an annular U-shaped bearing portion 11 having a plurality of ball-bearings 12 mounted therein. The revoluble section 10 is mounted within this U-shaped bearing 11 so as to engage the ball-bearings 12 therein. The lower terminal of the upper section 5 is provided with an integrally formed inverted U-shaped bearing portion 13 that is similar in construction to the bearing portion 11. Ball-bearings 14 are mounted in the bearing portion 13 and the upper terminal of the revoluble section 10 is also mounted within the bearing portion 13 so as to engage the ball-bearings 14 therein. It will thus be seen that the revoluble section 10 is adapt-

ed for free rotation relatively to the upper and lower sections 5 and 2, respectively.

The supporting braces 6, 7 and 8 each consists of a longitudinal bar having rectangular securing plates 16 and 17 at its upper and lower terminals. These securing plates 16 and 17 are provided with openings 18 through which suitable fastening means 19 may be inserted and have engagement with 10 the walls of the sections 5 and 2. Thus it will be seen that the supporting braces 6, 7 and 8 hold the upper section 5 in a rigid position, spaced from the upper terminal of the lower section 2 to permit the mounting 15 such as described of the revoluble section 10. It is preferable to construct the supporting braces 6, 7 and 8 of the same metallic bullet proof material as the sections of the turret 1.

20 As a means for permitting ventilation there has been provided a circular plate 20 that is secured in any suitable manner to the upper terminal of the upper section 5. This plate 20 is provided with a plurality 25 of perforations designated 21. Mounted upon the upper terminal of the upper section 5 is a conical cap 22 that is secured in the position above named by means of a plurality of downwardly extending and integrally formed securing strips 23 that are secured to the outer face of the section 5 by means of suitable fastening means 24 as will be clearly seen with reference to Fig. 1. This conical cap 22 is provided with a plurality of perforations designated 25. It will be apparent that ventilating means is provided for the turret through the medium of the perforated plate 20 and perforated conical cap 22. This cap 22 in being conical 40 prevents the lodgment of a stick of dynamite thereupon by the robbers and is formed of suitable metallic bullet proof material.

Mounted centrally of the upper and lower terminals of the revoluble section 10 are a plurality of fire arms supporting balls or spheres 26. I have shown four of these spheres 26 similarly arranged and equidistantly spaced but any number may be used. Each of the spheres 26 is provided with a 50 fire arm receiving bore 27 formed centrally through the spheres and adapted to receive the standard fire arm barrel. This bore 27 communicates along its upper terminal with a sight opening 28 which is formed through the spheres in superposed parallel relation to the bores 27 and is tapered toward its outer terminal so as to prevent the robbers from shooting through the sight openings and into the turret. A restricted portion 29 of 55 the sight opening is of sufficient size to permit the sight of the fire arm to be plainly seen and to enable the operator to see outwardly from the turret. The inner enlarged terminal 30 of the opening 28 permits a wide range of vision for the operator within

the turret and is approximately semicircular in cross section. The communication of the sight opening 28 with the bore 27 permits the operator within the turret to sight along the barrel of the gun to the gun sight.

A pair of opposed lugs 31 and 32 are formed at the inner terminal of the bore 27 adjacent the upper terminal thereof and are provided with set screws 33 and 34 which are mounted for adjustment therein. These lugs are disposed angularly with relation to the horizontal axis of the spheres 26 and the set screws 33 and 34 are disposed on the same plane consequently they are adapted for engagement with the opposed sides of the fire arm barrel so as to hold the barrel securely within the spheres. The inner portion of the spheres 26 extend into the turret a slight distance and are convex, therefore, access to the set screws 33 and 34 is readily had as they are disposed centrally of the inner convex portion of each sphere.

25 A bearing plate 35 having a central opening therein to permit free movement of the balls 26 is secured to the inner face of the revoluble section 10 adjacent each of the balls 26 by means of the screws 36. One face of this plate 35 is convex so as to conform to the curvature of the revoluble section 10 and to fit tightly thereagainst as 95 at 37. The above construction may be readily observed by reference to Fig. 4 in the drawings.

30 A door 38 is mounted within the lower section 2 and adapted to be locked in closed position by means of a lock 39 that is operable only from the interior of the turret as will be clearly seen with reference to Fig. 3 in the drawings. This door 38 is curved to conform to the curvature of the turret and 100 constructed of suitable bullet proof material. Suitable inside hinges may be employed for 105 swingingly securing the door.

35 In operation, the express messenger or guard upon the first signal of a robbery steps 110 into the turret 1 through the door 38 and immediately locks the door from the inside. The fire arms having been mounted in the balls 26 after the manner described may be trained as desired owing to the ability of the 115 section 10 to be rotated and the universal movement provided by the revolubility of the section 10 and the balls 26 so as to defend the contents of the express car or building in which the safety turret is mounted. 120

40 After the ammunition in one fire arm is exhausted the revoluble section 10 may be turned so as to permit the person within the turret to use one of the other fire arms carried by the revoluble section. It is apparent that the person within the turret may defend the contents of the car or building in which the turret is mounted in a reliable and efficient manner without the possibility of 125 being injured and that any attempt of the 130

robbers to plunder the car or building may be thwarted owing to the defensive powers given the person within the turret.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:-

1. A safety turret such as described comprising a cylindrical bullet proof base section adapted to be secured to the floor of a car or building, an upper cylindrical bullet proof section supported in spaced superposed relation to the base section, a plurality of spaced supporting braces secured terminally to the upper and base sections and holding them spaced apart, a bullet proof cylindrical section rotatably mounted between the upper and base sections, a plurality of fire arm supporting spheres mounted in said rotatable section, U-shaped bearing portions formed integral upon the lower and upper edges of the top and base sections respectively and receiving said rotatable section, ball bearings interposed between the edges of the revoluble section and bearing portions, means for removably securing the barrels of the fire arms within the supporting spheres carried by each supporting sphere and a door carried by the base section.
2. A safety turret such as described comprising a metallic bullet proof cylindrical base section adapted to be secured to a support, an upper metallic cylindrical bullet proof section supported in spaced superposed relation to said base section, means for supporting said upper section, a rotatable bullet proof section mounted between the upper and base sections, means for supporting fire arms and permitting their movement in any direction mounted in said rotatable section, means for securing said last named means to the rotatable section, means for rotatably supporting said rotatable section carried by the upper and base sections, a conical cap secured to the upper terminal of said upper section having a plurality of openings formed therethrough, and a plate secured to the upper terminal of said upper section beneath said cap and having a plurality of openings therein.
3. A safety turret such as described comprising a metallic bullet proof base section,

an annular U-shaped bearing formed integral with the upper terminal of said base section, an upper section constructed of bullet proof material supported in spaced superposed relation to said base section, means for supporting said upper section, an inverted U-shaped bearing formed integral with the lower terminal of said upper section, a cylindrical bullet proof rotatable section mounted within said bearing, a conical cap secured to the upper terminal of said upper section and having a plurality of openings formed therethrough, an annular plate secured to the upper terminal of said upper section beneath said cap and having a plurality of openings therein, means for adjustingly supporting fire arms loosely journaled in said rotatable section and a door carried by said base section.

4. A safety turret such as described comprising a plurality of cylindrical bullet proof sections, one of said sections being mounted for rotation relatively to the other sections and disposed intermediate the other sections, a plurality of fire arm supporting spheres mounted loosely within said revoluble section, said spheres having a fire arm receiving bore formed centrally therethrough and a sight opening formed in superposed parallel relation with the receiving bore, said sight opening being tapered toward its forward terminal and communicating with the receiving bore along its lower terminal, opposed lugs formed on each of said spheres adjacent to the larger end of said sight opening and having openings therein communicating with said fire arm receiving bore and screws mounted within said lugs to engage the barrel of a fire arm when said fire arm is inserted in the bore.

5. In a safety turret, a plurality of cylindrical sections, a plurality of fire arm supporting spheres loosely mounted within one of said sections, each of said spheres having a central circular fire arm receiving bore formed therethrough and a sight opening communicating with and arranged above said fire arm receiving bore, said sight opening being tapered toward its outer end, a pair of angularly disposed lugs formed on the opposite side of said fire arm receiving bore and having openings therein communicating with said bore and securing means adjustably mounted within said lugs to engage the barrel of a fire arm.

In testimony whereof I affix my signature in presence of two witnesses.

EDWIN A. STRATTMAN.
